CLAMP-AROUND AMMETER-VOLTMETER

Harvey A. Schwartz, Merrick, N.Y., assignor to Soss Manufacturing Company, Detroit, Mich., a corporation of Nevada

Filed July 11, 1967, Ser. No. 7,767

Term of patent 14 years

(Cl. D26—1)

FIG. 1 is a front view of a clamp-around ammeter-voltmeter, showing my new design in its closed position.

FIG. 2 is a rear view thereof.

FIG. 3 is a top view thereof.

FIG. 4 is a bottom view thereof.

FIG. 5 is one side view thereof.

FIG. 6 is the opposite side view thereof.

FIG. 7 is a front view showing the device in its open position.

The dominant features of the design reside in the full line portions of the drawings.

I claim:

The ornamental design for a clamp-around ammeter-voltmeter, substantially as shown and described.
